Fig. 2

FIG. 1 is a perspective view of an excavator boom and dipper handle assembly showing our new design;

FIG. 2 is a side view in elevation of the excavator boom and dipper handle assembly shown in FIG. 1;

FIG. 3 is a front view in elevation of the excavator boom and dipper handle assembly shown in FIG. 1;

FIG. 4 is a rear view in elevation of the excavator boom and dipper handle assembly shown in FIG. 1;

FIG. 5 is a plan view of the excavator boom and dipper handle assembly shown in FIG. 1;

FIG. 6 is a view in cross section of the excavator boom and dipper handle assembly taken through the plane 6—6 indicated in FIG. 2.

FIGS. 2—6 are on a slightly larger scale than FIG. 1.

The dominant features of the design reside in the portions shown in full lines. The dotted lines depicting a dipper and a crowd handle are for illustrative purposes only, and these particular dotted lines have been deleted in FIG. 6 for the sake of clarity.

We claim:

The ornamental design for an excavator boom and dipper handle unit, substantially as shown and described.
